CLAIM

The ornamental design for an automobile headlight, as shown and described.

DESCRIPTION

FIG. 1 is a perspective view of an automobile headlight; FIG. 2 is a front view thereof; FIG. 3 is a side view thereof; FIG. 4 is a top view thereof; and, FIG. 5 is a bottom view thereof.

The broken lines in the drawings depict portions of the article that form no part of the claimed design.

The drawings and descriptions disclose the right side embodiment. The claim is also for a mirror image left side embodiment.
